UNITED STATES PATENT OFFICE.

WILLIAM F. HELMOND, OF HARTFORD, CONNECTICUT, ASSIGNOR TO
UNDERWOOD TYPEWRITER COMPANY, OF NEW YORK, N. Y., A COR-
PORATION OF NEW JERSEY.

TYPE-WRITING MACHINE.

No. 838,328.

Specification of Letters Patent.

Patented Dec. 11, 1906.

Application filed April 3, 1906. Serial No. 309,661.

To all whom it may concern:

Be it known that I, WILLIAM F. HELMOND, a citizen of the United States, residing in Hartford, in the county of Hartford and State of Connecticut, have invented certain new and useful Improvements in Type-Writing Machines, of which the following is a specification.

This invention relates to means for guiding paper around the revoluble cylindrical platens of type-writing machines.

It is often desired to write close to the top and bottom edges of a sheet. This is usually found impracticable, because of the bulging of the paper, due to the bending of the same around the platen.

The object of the invention is to overcome this difficulty and to provide devices which may be readily applied to existing machines, especially those of the "Underwood" front-strike type, which will hold the entire top edge and the entire bottom edge of the paper against the platen, so as to permit writing very close to the edges, this being especially desirable at the bottom edge of the paper.

According to the invention a number of clips may be sprung upon the front roll-carrying rod of said machine at suitable intervals along the rod to bear yieldingly against the platen, close to the printing-line thereon, so that a line may be written along the very bottom edge of the paper. These clips are preferably formed of very thin springy sheet metal and are provided with clasps or loops which are sprung upon the rod and also with fingers which engage other rods upon the machine, so as to produce the proper pressure of the paper-guiding fingers upon the platen. The clips are intended principally to be applied to existing machines without alteration of the latter, and may be readily slipped onto or off from the machine.

In the accompanying drawings, Figure 1 is a front elevation of an Underwood type-writing machine, showing my improvements applied thereto. Fig. 2 is a sectional side elevation. Fig. 3 is an enlarged perspective view illustrating the relation of the paper-clips to the several rods of the usual roller mechanism. Fig. 4 shows how the paper-guiding fingers clear the lower-case types when the upper-case types are printing.

In said machine the platen 1 is provided with an axle 2, mounted in a platen-frame 3, the latter comprising a paper-shelf 4 in rear of the platen and continuing at 5 in the form of a plate or fingers extending around the under side of the platen in front thereof, said fingers being indicated at 6. Front and rear pressure-rolls 7 and 8 are provided beneath the platen, and adjustable paper-guides 9 control the paper as it rises above the printing-point.

The front rolls 7 are mounted at intervals upon a rod 10, carried or controlled by arms 11, said arms being pressed by springs 12 toward the platen, whereby the rolls are caused to bear with the required pressure upon the latter. Upon said rod 10 I secure a series of clips, (designated generally as 13.) Each clip 14 may be formed of very thin and extremely flexible sheet-steel or other metal. At the middle of the clip the metal is folded back at 15 and 16 and between the folds is curved to form a loop 17. This loop or eye extends 18 considerably more than half-way around the rod 10, but the metal is sufficiently flexible to permit the loop to open for attaching and detaching the clip. Said loop serves as a bearing for a pivotal action of the clip upon 19 the rod 10. Upwardly from said loop, which is formed transversely of the clip, extend two diverging paper-guiding fingers 20, reaching above the guides 6 and almost to the printing-line seen at 21, so as to hold the 22 lower edge of the sheet tightly against the platen until said edge has advanced too far for receiving impressions from the types, the latter being mounted upon type-bars 23. Owing to the extreme thinness of the metal 24 it clears the lower-case types 25, Fig. 4, while the upper-case types 26 are printing. Said types when printing are substantially in the same vertical plane and the platen in said machine shifts up and down to enable either 27 set of types to print. When the platen is shifted up, as at Fig. 4, there is a small space between the lower-case types and the platen; but this space is sufficient to receive the thin paper-clip 17, so that it will not be struck by 28 the lower-case type 25. Projecting downwardly from said loop is a long finger 29, whose lower end lies in rear of a rod 30 and bears against the rear side of the latter. Be-

tween the rods 23 and 10 is a third rod 24, which serves as a bearing for the fingers 22. Normally each finger 22 is sprung forwardly by the rod 24, thus tending to turn a clip 5 around the rod 10 in a direction to press the finger 17 against the platen, the finger 22 being sufficiently flexible for this action.

It will be seen that the fingers 22 may be readily inserted between the rods 23 and 24 10 and then the loops may be sprung upon the rod 10, so that the machine is easily provided with these guides, the latter being mounted upon the extreme ends of the rod 10 and also between the rolls 7, which are placed 15 at intervals along the rod.

The rolls 7 are released by means of a key 25, connected by a link 26 to the shaft 23, which is a rock-shaft and has the usual cam portions 27 to engage the arms 28, which are 20 integral with the arms 11, whereby the latter are dropped to release the rolls 7, the fixed rod or shaft 24 being the axis for such rocking motion. When the key 25 is depressed, the arms 11 and the rod 10 swing away from 25 the platen, together with the pressure-rolls 7 and the paper-clips 13, the spring-fingers 22 becoming relaxed, owing to the tendency of their tips to swing backwardly away from the rod 23. When the key 25 is restored to 30 normal position, the rod 10 is brought up toward the platen and the spring-fingers 22 again flexed about the rod 24, thereby causing the fingers 17 to bear against the platen.

If desired, the fingers 22 may be slightly 35 bowed, as at 22^a, to bear against collars 29, mounted upon the shaft 24.

Having thus described my invention, I claim—

1. In a type-writing machine having a 40 platen, the combination of a paper-clip formed at one end with a finger bearing upon the platen, and having at the other end a flexible finger, a stationary support upon which said flexible finger bears, said clip having between said fingers a transverse loop, and a rod upon which said transverse loop is detachably sprung.

2. In a type-writing machine having a 45 platen, the combination of a yielding flexible sheet-metal paper-clip having a loop, a rod upon which said loop is sprung, branched or diverging paper-guiding fingers extending in one direction from said loop and bearing upon the platen, a finger extending in the 55 opposite direction from said loop, and a support for the last-mentioned finger.

3. In a type-writing machine, the combination with a cylindrical platen, and paper-guiding means extending beneath and up in 60 front of the platen, of a rod in front of the platen, a series of paper-clips upon said rod, each clip having a loop sprung upon the rod, and a paper-guiding finger extending upwardly beyond said paper-guiding means 65 nearly to the printing-line, and also having a

flexible sheet-metal spring-finger projecting downwardly from said loop, a second rod below the platen and in front of said spring-fingers and engaged by the latter, and a third rod between said rods and in rear of said 70 spring-fingers, and serving as bearings for opposite sides of the latter, so that said spring-fingers are flexed, and the paper-guiding fingers caused to bear against the platen.

4. In a type-writing machine, the combination with a cylindrical platen, and paper-guiding means extending beneath and up in front of the platen, of a rod in front of the platen, a series of paper-clips upon said rod, each clip having a spring-loop engaging the 80 rod, and a paper-guiding finger extending upwardly beyond said paper-guiding means and to the printing-line, and also having a flexible sheet - metal spring - finger projecting 85 downwardly from said loop, a second rod below the platen and in front of said spring-fingers and engaged by the latter, and a third rod between said rods and in rear of said 90 spring-fingers, and serving as bearings for the latter, so that said spring-fingers are flexed, 95 and the paper-guiding fingers caused to bear against the platen; release-arms being mounted upon said third rod and carrying said first rod, and pressure-rolls being mounted upon said first rod, the construction being such 100 that when the arms are moved to release the rolls, the pressure between the spring-fingers and the third rod is relieved, and the paper-guiding fingers are moved away from the platen.

5. In a type-writing machine, the combination with a cylindrical platen, and paper-guiding means extending beneath and up in front of the platen, of a rod in front of the platen, a series of paper-clips upon said rod, 105 each clip having a spring-loop engaging the rod, and a paper - guiding finger extending upwardly beyond said paper-guiding means and to the printing-line, and also having a flexible sheet-metal spring-finger projecting 110 downwardly from said loop, a second rod below the platen and in front of said spring-fingers and engaged by the latter, and a third rod between said rods and in rear of said 115 spring-fingers, and serving as bearings for the latter, so that said spring-fingers are flexed, and the paper-guiding fingers caused to bear against the platen; said rolls being mounted at intervals along the first rod, and said clips being mounted both upon the extreme ends 120 of said rod and between the rolls.

6. In a type-writing machine, the combination with a cylindrical platen, and paper-guiding means extending beneath and up in front of the platen, of a rod in front of the 125 platen, a series of paper-clips upon said rod, each clip having a spring-loop engaging the rod, and a paper-guiding finger extending upwardly beyond said paper-guiding means and to the printing-line, and also having a flexi- 130

- ble sheet-metal spring-finger projecting downwardly from said loop, a second rod below the platen and in front of said spring-fingers and engaged by the latter, and a third rod between said rods and in rear of said spring-fingers, and serving as bearings for the latter, so that said spring-fingers are flexed, and the paper-guiding fingers caused to bear against the platen; release-arms being mounted upon said third rod and carrying said first rod, and pressure-rolls being mounted upon said first rod, the construction being such that when the arms are moved to release the rolls, the pressure between the spring-fingers and the third rod is relieved, and the paper-guiding fingers are moved away from the platen; said paper-guiding fingers being sufficiently thin to clear the lower-case types when lying between the latter and the platen at the printing of capital types. 75
7. In a type-writing machine having a platen, the combination with three supports in proximity to the platen, of a flexible sheet-metal paper-clip engaging all of said supports in succession and having a free end; said clip bearing in alternate directions against said supports, and the free end of the clip being caused by said supports to bear against the platen. 80
8. In a type-writing machine having a platen, the combination with three supports in proximity to the platen, of a flexible sheet-metal paper-clip engaging all of said supports in succession and having a free end; said clip bearing in alternate directions against said supports, and the free end of the clip being caused by said supports to bear against the platen; said clip having a loop formed therein to fit upon one of said supports. 85
9. In a type-writing machine having a platen, the combination with three rods in proximity to and parallel with the platen, of a flexible sheet-metal paper-clip engaging all of said rods in succession and having a free end; said clip bearing in alternate directions against said rods and the free end of the clip being caused by said rods to bear against the platen; said clip having a loop formed therein to fit detachably upon the rod which is nearest said free end. 90
10. In a type-writing machine having a platen, the combination with three supports in proximity to the platen, of a flexible sheet-metal paper-clip engaging all of said supports in succession and having a free end; said clip bearing in alternate directions against said supports, and the free end of the clip being caused by said supports to bear against the platen; said clip having a loop formed therein to fit upon one of said supports; and means for moving one of said supports to release the clip from the platen. 95
11. In a type-writing machine having a platen and a rod in proximity thereto; the combination of a flexible sheet-metal paper-clip and a support; said clip formed at one end with a finger bearing upon the platen and having at the other end a finger which bears upon said support, and having between said fingers a loop which is sprung upon said rod; the last-mentioned finger being sprung between the rod and the support to cause the first-mentioned finger to bear against the platen. 100
12. In a type-writing machine having a platen and a rod in proximity thereto and below the printing-line on the platen, the combination of a flexible sheet-metal paper-clip formed at one end with a finger bearing upon the platen, said finger extending upwardly from said rod nearly to the printing-line, and supporting means engaging another finger formed upon said clip and coöperating with the rod to press the first finger against the platen. 105
13. In a type-writing machine having a platen and a rod in proximity thereto and below the printing-line on the platen, the combination of a flexible sheet-metal paper-clip formed at one end with a finger to bear upon the platen, said finger extending upwardly from said rod nearly to the printing-line, and means engaging opposite sides of a downwardly-extending finger formed upon said clip to flex the same and coöperating with the rod to press the first finger against the platen. 110
14. In a type-writing machine having a platen and a rod in proximity thereto and below the printing-line on the platen, the combination of a flexible sheet-metal paper-clip formed at one end with a finger bearing upon the platen, said finger extending upwardly from said rod in juxtaposition to the printing-line, and supporting means engaging another finger formed upon said clip and coöperating with the rod to press the first finger against the platen; said clip being formed between said fingers with a loop which is sprung upon said rod. 115
15. In a type-writing machine having a platen and a rod in proximity thereto and below the printing-line on the platen, the combination of a flexible sheet-metal paper-clip formed at one end with a finger to bear upon the platen, said finger extending upwardly from said rod nearly to the printing-line, and means engaging another finger formed upon said clip and coöperating with the rod to press the first finger against the platen; said clip being formed between said fingers with a loop which is detachably sprung upon said rod; and means for moving said rod away from the platen to release the clip. 120
